F. E. MUELLER

SPINNING SPINDLE

Filed Jan. 2, 1922

Frederick E. Mueller
INVENTOR.
BY *C. P. Goepel.*
ATTORNEY.

UNITED STATES PATENT OFFICE.

FREDERICK E. MUELLER, OF MOUNT VERNON, NEW YORK, ASSIGNOR TO NORMA-HOFFMANN BEARINGS CORPORATION, OF LONG ISLAND CITY, NEW YORK, A CORPORATION OF NEW YORK.

SPINNING SPINDLE.

Application filed January 2, 1922. Serial No. 526,457.

To all whom it may concern:

Be it known that I, FREDERICK E. MUELLER, a citizen of the United States, residing at Mount Vernon, in the county of Westchester and State of New York, have invented certain new and useful Improvements in Spinning Spindles, of which the following is a specification.

This invention relates to spinning spindles having ball bearings of relatively large size whereby the spindle may be operated at high speeds and with an economical consumption of power.

In one embodiment of the invention the bolster of a conventional form of spindle is provided at its upper end with a cylindrical extension or sleeve surrounded by the whirl which is fixed to the spindle proper. Between the spindle and the upper end of the sleeve or extension on the bolster, a ball bearing is interposed. The principal feature of novelty resides in the utilization by a simple and economical construction of a sleeve or cylindrical extension on the bolster as the outer race for the bearing balls, thus enabling balls of relatively large size to be employed within the relatively small space which is available between the periphery of the spindle and the sleeve. Owing to the fact that we thus eliminate the use of a separate outer race for the bearing constituting a unit part of the bearing, we are also enabled to provide a ball-retaining cage which is of relatively heavy and durable construction.

It is a further general object of the invention to provide a ball bearing for spindles, the several parts of which can be produced by means of simple, mechanical operations and readily assembled in connection with the remaining parts of the spindle or disassembled when repair or inspection is necessary.

With the above and other objects in view, the invention consists in the improved spindle bearing and in the form, construction and relative arrangement of the several parts as will hereinafter be more fully described and subsequently incorporated in the subjoined claims.

In the accompanying drawing wherein I have illustrated a conventional type of cotton spinning spindle equipped with my new invention, I have shown a central vertical

section through the spindle base, the bolster and the whirl.

In practice, it is usual to mount a large number of the spindles in spaced relation to each other upon a supporting rail, each spindle including a base 5 which is removably mounted or fixed upon the rail in any approved manner. This base is provided with the customary tubular or hollow shank 6 to receive a bolster 7. This bolster intermediate of its ends is provided with a peripheral bearing surface 8 for contact with the inner wall of the shank 6, the remaining peripheral surfaces of the bolster being slightly spaced from the wall of said shank so as to permit of a slight angular movement of the bolster with respect to the base. An oil film is interposed between the spaced surfaces of the bolster and the base to yieldingly cushion such relative movement.

The upper surface of the base 5 is provided with a circular recess 9 to the annular vertical wall of which the lower end of a tubular sleeve or cylinder 10 is fixed in any preferred manner. The upper end of the bolster 7 is diametrically enlarged or formed with the head 11 which loosely fits within the lower portion of the sleeve or cylinder 10. To this bolster head the lower end of a second sleeve or cylinder 12 is suitably secured, said latter sleeve extending upwardly above the bolster.

The spindle proper, indicated at 13, is mounted at its lower end in the bolster 7 in the usual manner and extends upwardly above the cylinder or sleeve 12 fixed to the upper end of said bolster. This spindle carries the usual whirl 14 which encloses or surrounds the outer cylinder 10 fixed to the base 5.

The several parts of the spindle to which I have above referred, together with the lubricant-supply means illustrated in the drawing, constitute no part of my present invention. I am aware of the fact that ball bearings have heretofore been used in the operation of such spindles, but owing to the limited permissible diameter of the whirl 14, the bearing balls have necessarily been of an exceedingly small size so that they were incapable of withstanding the excessive wear incident to high-speed operation of the spindle for an extended length of time. It must be remembered that when I

just spoke of ball bearings I include therein in the inner race, the outer race, balls between the races and a cage for the balls. I have just stated that the balls were relatively small and it is also clear that the cage would be correspondingly small and fragile.

In my present invention I aim to overcome the deficiencies of ball bearings previously used in such spindles, as above referred to, and to this end I utilize the upward extension of the inner cylinder 12 fixed to the bolster, as the outer race for the balls so that the bearing is not provided with a separate outer race ring as a unitary part thereof. As herein shown, the bearing consists in an inner race ring 15 fixed upon the spindle 13 in any approved manner and provided with an annular ball-receiving race in its outer face. An inner race of this form is well known in the art. The bearing balls 16 are assembled and held in circumferential spaced relation in the race of the inner ring 15 by means of a retaining cage 17. This cage, which is of a well known form, includes continuous side flanges disposed at opposite sides of the series of balls and a connecting wall between said flanges having spaced openings therein through which the inner portions of the balls protrude for engagement in the race of the inner bearing ring 15. Because this cage is of a well known type I do not show it in detail in the drawings but reference to a suitable cage is made by referring to U. S. Letters Patent 3,53 to Hirth No. 796,648 of August 8, 1905. The bearing balls at their outer sides have bearing contact with the inner face of the tubular extension or sleeve 12 fixed to the bolster head 11. It will be apparent that considerable space is afforded between the inner bearing rings 15 and this cylindrical inner wall so that balls of relative large diameter may be employed together with a cage 17 of strong and durable construction due to the large size of the cage which may be used. In the illustrated embodiment of my invention I have shown two of the inner bearing rings 15, each having a series of balls in assembled relation therewith. However, it is practically possible to make the two bearing rings in the form of one unitary part having two spaced annular race-ways. The separate rings 15 or the race-ways formed in a single inner bearing ring may be spaced apart on the spindle for any desired distance within certain limits so that the distance between the contact points of the spaced series of balls with the outer common cylindrical sleeve 12 may be varied in such manner as to secure the highest degree of efficiency in the operation of the spindle.

Another advantage incident to the utilization of the bolster sleeve or cylinder 12 as an outer race ring for the bearing, resides in the fact that this cylinder or sleeve may be

removed from the bolster head 11 and its position thereon reversed so as to provide new bearing surfaces for the balls 16 at the opposite end of the sleeve, should this become necessary, in order to obviate looseness and noise in the bearing and to prolong the life thereof.

It will be noted that the inner cylindrical tubular surface of the cylinder 12 is cylindrical throughout without any projections thereon which might limit the movement of the balls with respect to the inner cylindrical surface. This permits the inner race, the balls and the cage to be withdrawn from the cylinder 12 without interference by simply lifting the spindle.

From the above description considered in connection with the accompanying drawing, the construction and several advantages of my present invention will be readily understood. It will be appreciated that by eliminating the use of an outer race ring as a unitary part of the bearing, such spinning spindles may be equipped with bearings having balls of relatively large diameter to thereby materially prolong the life of the bearing. Also, the necessity of employing holding or securing means for the outer race ring or special machining operations so as to retain said ring in a fixed position is avoided. By providing the bearing with a cylindrical outer race which may serve as a common race member for a plurality of rows of bearing balls, the expense incident to the manufacture of such bearings and the equipment of the spindle therewith is also materially reduced.

I have herein disclosed an embodiment of the invention which I believe will give highly satisfactory results in practical operation. Nevertheless, it is to be understood that the improvement constituting the subject matter of this application is susceptible to certain minor modifications in the several structural features above referred to. Accordingly the privilege is reserved of resorting to all such legitimate changes in the form, proportion and relative arrangement of the several parts as may be fairly embodied within the spirit and scope of the invention as claimed.

What I claim is:

1. In combination with a spindle including a base and a bolster mounted therein to receive the spindle proper, a cylindrical sleeve fixed to the upper end of the bolster, and an anti-friction bearing for the spindle including an inner bearing ring fixed to the spindle, a ball-retaining cage and a series of bearing balls assembled therein and interposed between the inner bearing ring and the inner surface of the cylindrical sleeve on the bolster, said inner surface of the sleeve constituting a bearing race for the balls and being unobstructed to permit of the removal or insertion of the inner bearing ring, the

balls and the cage from said sleeve as a unit when the spindle is removed from the bolster.

2. A spinning spindle comprising a base, a bolster supported therein and provided with a head which extends above said base, a cylindrical tubular extension fixed at its lower end to said head and extending upward therefrom, a spindle supported in said bolster and provided with a whorl which encloses said tubular extension and with an inner race ring within said extension, bearing balls engaging with said race ring and having direct bearing contact at their outer sides with the spindle with the inner peripheral surface of or to said extension, and a tubular cylindrical extension fixed at its lower end to said head and extending upward between said first named cylindrical extension and said whorl and spaced from both.

3. In combination with a spindle having a base and a bolster mounted therein to receive the spindle proper, a whorl for the spindle, a reversible sleeve fixed at one end to the upper end of said bolster and having an uninterrupted and unobstructed inner surface area, and an antifriction bearing interposed above the bolster and within the whorl between the spindle proper and the inner surface of said sleeve, said surface constituting the outer race for direct contact engagement of the rotating elements of the bearing therewith, said spindle and whorl, with the antifriction bearing being adapted to be removed or inserted within the reversible sleeve, the lower end of the spindle having contactual bearing engagement in the bolster thereby, allowing the ready removal or insertion of the spindle from or into the bolster base.

4. In combination with an outer bearing race member for spindle bolsters, comprising a cylindrical sleeve having an interior surface unobstructed and uninterrupted, and adapted at one of its ends to engage the spindle bolster, of a spindle having a whorl, said spindle provided within the whorl with an inner race and ball bearings, said ball bearings adapted to make direct contactual engagement with the unobstructed and uninterrupted interior surface of the cylindrical sleeve, and said spindle being adapted to be removed from or inserted into the bolster without disassembling the ball bearings from the spindle, all of the ball bearings being above the bolster allowing a free removal or insertion of the lower end of the spindle in respect to the bolster.

5. In combination with a base, a bolster 60 therein, and a spindle removably supported in the bolster; a vertically disposed cylindrical sleeve fixedly mounted at one of its ends relative to the spindle and extending above the upper end of the bolster, the upper 65 portion of the sleeve having an uninterrupted inner surface area, and an antifriction bearing unit interposed between the spindle and said inner surface of the sleeve and consisting of an inner race ring fixedly 70 engaged upon the peripheral surface of the spindle, a cage surrounding said race ring, and a plurality of bearing elements mounted in said cage and having rotating contact with the race ring and with said uninterrupted inner surface of the cylindrical sleeve whereby said bearing unit may be withdrawn through the upper end of the sleeve when the spindle is removed from the bolster.

6. In combination with a base, a bolster mounted therein and a spindle removably supported in said bolster; a vertically disposed reversible cylindrical sleeve fixedly mounted at one of its ends relative to the 65 spindle and extending above the upper end of the bolster, said sleeve having an uninterrupted inner surface area, and a plurality of anti-friction bearing units interposed between the spindle and the inner surface of 70 the sleeve, each of said units including an inner race ring fixedly engaged upon the peripheral surface of the spindle, and a series of bearing elements having rotating contact with said race ring and the uninterrupted inner surface of the cylindrical sleeve whereby said bearing units may be withdrawn through the upper end of said sleeve when the spindle is removed from the bolster.

7. In combination with a base and a spindle removably supported therein; a vertically disposed cylindrical sleeve detachably mounted at one of its ends in fixed relation to the spindle and reversible end for end, said sleeve having an uninterrupted inner surface area, and an anti-friction bearing unit interposed between the spindle and said inner surface of the sleeve and withdrawable through the upper end of said sleeve with the spindle when the latter is removed from its operative position relative to the spindle base.

In testimony that I claim the foregoing as my invention, I have signed my name 115 hereunder.

FREDERICK E. MUELLER.
